UNITED STATES PATENT OFFICE

107,341

DESIGN FOR AN ESCUTCHEON PLATE FOR RADIO RECEIVERS

Richard C. Marholz, Chicago, Ill., assignor to
Belment Radio Corporation, Chicago, Ill., a
corporation of Illinois

Application October 7, 1937, Serial No. 72,050

Term of patent 7 years

To all whom it may concern:

Be it known that I, Richard C. Marholz, a citizen of the United States, residing at Chicago, in the county of Cook and State of Illinois, have invented a new, original, and ornamental Design for an Escutcheon Plate for Radio Receivers, of which the following is a specification, reference being had to the accompanying drawing, forming part thereof, in which:

Figure 1 is a front view of my design for an escutcheon plate for radio receivers, and
Figure 2 is an end elevation thereof.

I claim:

The ornamental design for an escutcheon plate for radio receivers as shown.

RICHARD C. MARHOLZ.
